Atty's.

UNITED STATES PATENT OFFICE.

FRANK S. BUCK, OF SPRINGFIELD, VERMONT, ASSIGNOR, BY MESNE ASSIGNMENTS, TO FITZ-EMPIRE DOUBLE PIVOT LAST CO., OF ROCHESTER, NEW YORK, A CORPORATION OF MAINE.

CUTTER INSTRUMENT FOR WOOD-TURNING LATHES.

1,361,305.

Specification of Letters Patent.

Patented Dec. 7, 1920.

Application filed April 10, 1915. Serial No. 20,433.

To all whom it may concern:

Be it known that I, FRANK S. BUCK, a citizen of the United States, and resident of Springfield, in the county of Windsor and 5 State of Vermont, have invented certain new and useful Improvements in Cutter Instruments for Wood-Turning Lathes, of which the following is a specification.

The present invention relates to cutting means especially adapted for use in machines 10 for turning irregular forms from wood, such as lasts and other irregular articles. Difficulty has been experienced in the use of the cutter head heretofore used in the last lathe 15 due to trouble in properly mounting and gaging the cutters and to lack of interchangeability of the cutters. My invention provides a novel organization of cutter head which provides for the interchangeability 20 of cutters including a simplified construction for mounting them on the cutter head, and for easy and accurate gaging of their positions.

In the drawings I have illustrated two 25 embodiments of cutter head illustrating the principles embodied in my invention, and have shown in connection with both heads the cutters used therewith, the same sort of cutter being employed in each instance. The 30 cutter heads here shown are respectively what is called the "large cutter head" for use in turning ordinary irregular forms in wood, and what is called the "small cutter head" for cutting forms which have deep 35 concavities of short radius, such as certain special forms of last which are known as hollow sided lasts.

Figure 1 is an end view of the large cutter head.

40 Fig. 2 is a cross section of the cutter head taken on line 2-2 of Fig. 1 and represented as viewed from the right hand side of such line.

Fig. 3 is a development view showing the 45 several arms of the cutter head in side elevation and represented as placed side by side.

Fig. 4 is a diagrammatic view illustrating the paths in which the several cutters travel.

50 Fig. 5 is a cross section through the center of one of the cutters and the adjacent arm of the cutter head on a plane perpendicular to the axis of the head.

Fig. 6 is a perspective view of the small

cutter head showing the roughing cutters 55 in connection therewith.

Fig. 7 is an end view of the small cutter head partly in section.

Fig. 8 shows the cutter gage.

The same reference characters indicate the 60 same parts in all the figures.

Referring to the drawings and first to Figs. 1 to 4 inclusive which show the large cutter head, such head is seen to comprise a hub 10 and a number of arms 11, 12, 13, 14, 15, 65 and 15 projecting from the periphery of such hub. In the illustrated embodiment there are five such arms which project approximately radially and are spaced at equal angular intervals about the center of the 70 hub. I may, however, construct the head with more or fewer of such arms.

Each of the arms carries a cutter, the several cutters being shown at 21 on arm 11; 22 on arm 12; 23 on arm 13; 24 on arm 14 75 and 25 on arm 15. These cutters and the means of attaching them to the arms by which they are respectively carried, are all alike, wherefore a description of one will suffice for all, and the cutter 21 will be taken 80 as the example for such a description.

Such a cutter is cup-shaped, being open at one end 26 and having an end wall or bottom 27 at the other end in which there is a passage 28. In the outer face of the end wall 85 is a diametral groove 29 which fits, and is adapted to slide on, a rib or guideway 30 formed on the adjacent face of the arm 11 and extending longitudinally of such arm. A bolt 31 passes through the arm 11 and 90 through the hole 28 in the end wall of the cutter, and the head 32 of such bolt bears on such end wall and overlaps the margin of the hole. A nut 33 is screwed on the shank of the bolt on the opposite side of the arm 11 95 from the cutter, and is set up to bind the cutter tightly against the arm. The hole 28 is somewhat larger in diameter than the shank of the bolt to permit an adjustment of the cutter along the guideway 30, that is 100 in and out with respect to the center of the cutter head, for a purpose which will appear later.

Externally the cutter is tapered from the open end at which the diameter of the cutter is greatest, to the end next to the arm, where the diameter is least, so that the external surface of the cutter is that of a cone. Inter-

nally the cutter is beveled at 34 near the open end so as to form a cutting edge at the margin of such open end. The outer side of such cutting edge, that is, the side more remote 5 from the axis of the cutter head, is the part which acts on the work, and is more remote from the axis than any other part of the cutter; while the axis of the cutter itself is substantially perpendicular to a plane passing 10 through the axis of the cutter head and intersecting the cutter. These conditions are found in each of the cutters of the entire cutter head, and enable the cutter instrument to act on rotating irregular forms to produce 15 curved surfaces. The cutter has one or more openings 35 in its sides near the base thereof, that is, near the end which bears against the arm. Two such openings, disposed on respectively opposite sides of the cutter, are 20 here shown, but I may provide only one, or more than two. The purpose of the openings is to permit escape of chips and also to permit passage of air and thus diminish the displacement and pressure of air when the 25 head is running.

By reference to Fig. 1 it will be seen that the arms of the cutter head are of different lengths, the arm 11 being shortest and the other arms of successively increasing length 30 up to the arm 15, which has the greatest length. This same feature is shown by Fig. 4, and the latter view also shows that the outer ends of the arms are differently offset axially from a plane perpendicular to the axis of the cutter head. The intersections of such a plane with the various arms of the cutter are shown in the different parts of Fig. 3 by the lines marked "C-L" in each of these parts. The plane chosen for 35 illustration of this feature passes through the center of the cutter on arm 15 and to the right of the centers of the cutters on arms 14, 13, 12, and 11 by increasing amounts. By reason of these differences in 40 axial and radial offsetting or projection, the several cutters travel in different circular paths, the cutter 11 traveling farthest to the left and nearest to the axis of the cutter head, and the other cutters being progressively at the right and outside of the path 45 of cutter 1. These paths are diagrammatically illustrated in Fig. 4, where the circles marked 11, 12, 13, 14, and 15 represent the cutting edges of the cutters on the 50 arms similarly marked in Fig. 1, and show the positions which these edges successively 55 occupy when crossing the same line, such as the line 2-2, above the axis of the cutter head. The line C-L in Fig. 3 represents 60 the plane which is designated by the same letters in Fig. 4.

The above described relation of the cutters is employed for machines in which the cutter carriage is fed to the left, or the 65 work is fed to the right so that the cutting

action progresses on the work from right to left. For machines in which the feed is otherwise, the direction of axial offsetting of the several cutters may be appropriately modified, within the scope of this invention. 70 This relation causes the cutters to come into action successively on the work, the first four cutters removing surplus stock, and the last cutter 15 bringing the work piece to finished form. The cutters 11, 12, 13 and 14 75 may, therefore, be considered as roughing cutters and the cutter 15 as a finishing cutter. It is to be understood that the cutter is used in connection with a model and a guide which bears on the model at a point 80 corresponding to the point on the work which is engaged by the finishing cutter, as usual in machines of the character indicated to which the present invention is applied.

The particular cutter herein shown has 85 a number of advantages. First the cutters are alike, and any one may be used on any arm, whereby the manufacturer, instead of having to keep in stock a number of different types of cutter for the same machine, 90 need supply only one type.

The circular outline of the cutter and its mode of mounting on the carrier arm enables the cutter to be turned around when one part of the edge becomes dull. Not 95 more than half of the cutting edge is used in one position of the cutter, so that when the used part of the edge is dull, that portion may be replaced by the unused part of the edge upon simply loosening nut 33, 100 turning the cutter half way around upon the bolt 31, reengaging the groove 29 with the guide 30, and again setting up the nut 33. In some instances the roughing cutters use less than half of the cutting edge, and 105 so by providing two or more grooves 29 in the cutter at right angles to each other, or at other angles, the cutter may be positioned by turning it through less than 180° so as to present an unused part of the edge in the 110 cutting location.

The comparatively great axial length of the cutter provides a long working life, since the cutter may be ground back in sharpening until its edge is brought almost to the 115 lateral openings 35, before it is used up.

The radial adjustability of the cutter on the arms enables it to be shifted outwardly as its edge is carried back by sharpening, so that even though after repeated sharpenings 120 its edge is no longer as far from the axis of the cutter head as when new, the adjustment on the arm permits the cutting side of the edge to be brought out into the required location. 125

After the finishing cutter has been used up by sharpening beyond the limit at which it can be adjusted for use as a finishing cutter, it may be placed on the arm of the last roughing cutter, used there to the limit of 130

adjustment on that arm, and used successively on the preliminary roughing cutter arms. Thus the cutters may be effectively used as long as sufficient material remains 5 to form a cutting edge.

The small cutter head shown in Figs. 6 and 7 consists of a central hub 40 provided with a keyway 41, which is keyed upon a spindle 42. This hub has two arms 43, each 10 provided with a guiding rib 44 on the side which advances in the rotation of the cutter head. Each arm carries a cutter 45 having approximately the same characteristics and substantially the same form as the cutters 15 previously described, which is secured by a screw 46 passing through a hole 47 in the closed end of the cutter and tapped into the arm 43. Cutter 45 is a cup-like piece with a tapering exterior, largest at the open end 20 and having a cutting edge 48 at such open end. It is adapted to be adjusted outwardly on the arm as the diameter of its cutting edge becomes reduced by sharpening, in the same manner as the cutters previously 25 scribed, and is otherwise arranged similarly thereto.

The two cutters on the arms of the head 40 are used as finishing cutters and both are at the same distance from the axis and are 30 in the same zone surrounding the axis. Roughing cutters are used as a part of the cutter instrument of which the above described finishing cutter is a part. Three such roughing cutters are shown in Fig. 6. 35 The first roughing cutter consists of a collar 49 keyed upon the shaft and having two blades 50. The second roughing cutter consists of a collar 51 and two blades 53. The third cutter consists of a collar 54 and blades 40 55. These collars are all keyed upon the spindle 42 with spacing rings 56, 57, between them which hold the collars at the proper distance apart. The blades on the first and second cutters project toward the second 45 and third cutters, respectively, over the intermediate spacing rings and also project laterally from the collars on which they are respectively mounted, so that the edges of such blades extend throughout their 50 entire length, and the paths in which the several cutters travel are contiguous to one another. The cutting edges of these blades are slightly inclined with respect to the spindle 42 outwardly toward the finishing 55 cutter and the surfaces of revolution generated by the several edges form zones of what is approximately a continuous conical surface. The blades of the different cutters are, however, spaced about the axis of the 60 shaft so as to break up the chips and distribute the cutting effort. It should be mentioned that the finishing cutter head is secured by a screw 58 which is threaded into the end of the shaft against a shoulder countersunk within the end of the head 40 and 65

that the recess in the head 40 occupied by the head of the screw 58 is deeper than such screw head so as to admit the central part 59 of a gage 60 to be used in setting the cutters 45 both at the same distance from the axis 70 of the spindle, so that both finishing cutters will do their shares of the work.

It is intended that the small cutter instrument be set with its axis of rotation at an acute angle to the axis of the rotation of the 75 work, as clearly described in my prior Patent No. 1,137,117, dated April 27, 1915, and pending application Serial Number 20,432, filed April 10, 1915, in order that the bearings for the cutter spindle may clear the 80 work and that the other advantages of the invention of the patent may be secured. The short radius of the small cutter head enables the same to cut concavities in the work 85 of a sharper curvature than can be cut by the large cutter head.

The small cutter last described is part of a cutter instrument which comprises roughing cutters and one or more finishing cutters 90 axially disposed along the cutter instrument and projecting to different extents from the axis of such instrument. The same characterization applies to what I call the "large cutter head," which also is a cutter instrument having roughing cutters and a finishing 95 cutter offset from one another axially of the instrument and at respectively different distances from the axis thereof. Essentially the same character of cutter is used in both forms of the instrument, that is a cup shaped 100 cutter having a circular cutting edge at one end; and each cutter may be reversed or turned when the edge at one side becomes dull, whereby to place an unused part of the edge in cutting position; and may be adjusted outwardly as the cutting edge is carried back by grinding.

What I claim and desire to secure by Letters Patent is:

1. A cutter instrument for use in a last 110 lathe comprising a head adapted to rotate on an axis and having an arm extending transversely to the axis, a conical cup-shaped cutter mounted on the arm with the mouth of the cup extending toward the direction of 115 rotation, the lip of the cup forming the cutting edge, and a rib and slot engaging means between the arm and cutter extending transversely to the axis of rotation, and in a plane perpendicular to the said axis, whereby the 120 cutting edge may be adjustable to proper position as the cutter is ground, and whereby the cup-shaped cutter may be reversed and held positively in either position in order to bring different parts of the cutting 125 edge into use.

2. A cutter instrument for use in a last 130 lathe comprising a head adapted to rotate on an axis and having a cutter adjustably mounted thereon at a distance from the axis,

the head having a depression with its center in the axis of rotation and which is available for gaging purposes whether the cutter be off or on its spindle, and a gage constructed and arranged to enter the depression and be centered thereby and to engage the cutter whereby the cutter may be properly positioned.

3. A cutter instrument for use in a last lathe comprising a head adapted to rotate on an axis and having a cutter adjustably

mounted thereon at a distance from the axis, a gage for adjusting the cutter and interfitting means between the gage and head, constructed and arranged to center the gage in the head on the axis of rotation, that part of the interfitting means carried by the head being always available for gaging purposes.

In testimony whereof I have affixed my signature.

FRANK S. BUCK.
